Des. 226,353
Patented Feb. 20, 1973

226,353

HOSPITAL IN-PATIENT SERVICE CORE MODULE

John R. Schultz, John M. Sharer, and John W. Heidacher,
Batesville, Ind., and Frank M. Damico, Cincinnati,
Ohio, assignors to Hill-Rom Company, Inc., Batesville,
Ind.

Filed May 3, 1971, Ser. No. 140,013

Term of patent 14 years

Int. Cl. D24—01

U.S. Cl. D13—1 L

FIG. 1 is a perspective view of the hospital in-patient service core module as seen from the right hand side thereof;

FIG. 2 is a perspective view of the hospital in-patient service core module as seen from the left hand side thereof; and

FIG. 3 is a top side plan view of the hospital in-patient service core module.

What is claimed is:

The ornamental design for a hospital in-patient service core module, as shown and described.
